(57) **CLAIM**

We claim the ornamental design for a light-emitting diode array, as shown and described.

DESCRIPTION

FIG. 1 is a perspective view of the first embodiment showing the claimed design;

FIG. 2 is another perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1;

FIG. 8 is a bottom plan view of FIG. 1;

FIG. 9 is a perspective view of the second embodiment showing the claimed design;

FIG. 10 is another perspective view of FIG. 9;

FIG. 11 is a front elevational view of FIG. 9;

FIG. 12 is a rear elevational view of FIG. 9;

FIG. 13 is a left side elevational view of FIG. 9;

FIG. 14 is a right side elevational view of FIG. 9;

FIG. 15 is a top plan view of FIG. 9;

FIG. 16 is a bottom plan view of FIG. 9;

FIG. 17 is a perspective view of the third embodiment showing the claimed design;

FIG. 18 is another perspective view of FIG. 17;

FIG. 19 is a front elevational view of FIG. 17;

FIG. 20 is a rear elevational view of FIG. 17;

FIG. 21 is a left side elevational view of FIG. 17;

FIG. 22 is a right side elevational view of FIG. 17;

FIG. 23 is a top plan view of FIG. 17; and,

FIG. 24 is a bottom plan view of FIG. 17.
